S. G. MEWBORN

LOOSE LEAF BINDER

Filed Jan. 16, 1923

Patented Aug. 7, 1923.

1,464,185

UNITED STATES PATENT OFFICE.

SIDNEY G. MEWBORN, OF WILSON, NORTH CAROLINA.

LOOSE-LEAF BINDER.

Application filed January 16, 1923. Serial No. 612,996.

To all whom it may concern:

Be it known that I, SIDNEY G. MEWBORN, a citizen of the United States, residing at Wilson, in the county of Wilson and State of North Carolina, have invented certain new and useful Improvements in Loose-Leaf Binders, of which the following is a specification.

My invention relates to improvements in loose leaf binders.

An important object of the invention is to provide a device for detachably holding the loose leaves, which device is longitudinally adjustable to fit leaves of different lengths, with the rings or holding elements independently longitudinally adjustable, so that they may properly register with the openings formed in the leaves.

A further object of the invention is to simplify the construction of the holding elements, rendering them cheaper to manufacture and more reliable in operation.

Other objects and advantages of the invention will be apparent during the course of the following description.

In the accompanying drawings forming a part of this specification and in which like numerals are employed to designate like parts throughout the same,

Figure 1 is a horizontal sectional view taken on line 1—1 of Figure 2,

Figure 2 is a vertical longitudinal sectional view taken on line 2—2 of Figure 1,

Figure 3 is a transverse vertical sectional view taken on line 3—3 of Figure 2,

Figure 4 is a plan view of one of the holding elements, and,

Figure 5 is an end elevation of the same.

In the drawings, wherein for the purpose of illustration is shown a preferred embodiment of my invention, the numeral 10 designates a cover, embodying sides 11, foldable at 12 upon a back 13. This cover may be of any well known or preferred construction.

The holding device embodies an adjustable base, including base-guides 14, which are curved in cross-section, as clearly illustrated in Figure 1. These base-guides are provided at their longitudinal edges with over-hanging flanges 15. The base-guides 14 are formed separate and are therefore adjustable longitudinally toward and away from each other, corresponding to the length of the cover 10, or the leaves 16. The base-guides 14 may be attached to the back 15

of the cover, by any suitable means, and as illustrating one form of means, I have shown attaching elements 17, in the form of McGill fasteners, which pass through apertures in the base-guides 14 and apertures in the back 13, and have their ends bent outwardly or flattened. The invention is in no sense restricted to this form of attaching elements, as any other suitable form of means may be employed.

I preferably provide three separate holding devices, which are individually longitudinally adjustable within the guide-bases. These holding devices embody bases 18, slidably mounted within the base-guides 14. The intermediate base 18 spans the space between the inner ends of the base-guides, and also serves to connect these base-guides. The intermediate base provides means whereby the base-guides 14 may be longitudinally adjusted with respect to each other, and remain connected. Of course the intermediate base 18 may also be shifted longitudinally with respect to the base-guides, as is the case with the outer base 18. Each base 18, Figure 1, is curved in cross-section, and is provided at its edges with inwardly extending curved flanges 19, slidably within the flanges 15. The base-guides 14 and the base 18, both being curved in cross-section, are suitably stiff and resilient, transversely.

Each base 18 carries a ring or loop 20, which embodies two sections 21. Each section 21 is formed of suitably stiff wire, bent to form a loop element 22. The wire is then bent at the point 23, forming a U-shaped foot 24, including an inner arm 25, projecting longitudinally beyond the point 23. The inner arms 25 of these feet 24, are in permanent contact, and are pivotally bound together by a sleeve or clip 26, placed thereon, as shown. The base-guide 14 and base 18, which are hollow, face in opposite directions, and hence provide ample space, for receiving the feet 24 and associated elements.

In the use of the holder, the base-guides 14 are first suitably longitudinally adjusted upon the back 13, and are then secured thereto by means of the attaching elements 17. The bases 18 are carried within these base-guides. When the loose leaves 16 are presented to the holding devices, should the loops 21 not properly register with the openings in the leaves, the base or bases

18 may be properly longitudinally adjusted, for this purpose. The loop elements 22 are opened by swinging them apart, and when they are shifted to the opened position, they 5 will be held in this position, since the U-shaped feet 24 will be swung to one side of dead center. When the loop elements 22 are shifted to the closed position, they are locked in this closed position, since the feet 10 24 are either at dead center or a little to one side of dead center.

In view of the foregoing description, it will be seen that I have provided a holding device for loose leaves, which possesses a 15 large range of adjustability, is highly convenient in use, and reliable in operation.

It is to be understood that the form of my invention herewith shown and described is to be taken as a preferred example of the 20 same, and that various changes in the shape, size, and arrangement of parts may be resorted to without departing from the spirit of my invention or the scope of the subjoined claims.

25 Having thus described my invention, I claim:

1. In a loose leaf binder, a cover having a back, a plurality of base-guides adapted to be longitudinally adjustably mounted 30 upon the back and to be secured thereto in

a selected adjusted position, a plurality of bases longitudinally adjustably mounted within the base guides, and holding elements carried by the bases.

2. In a loose leaf binder, a cover having a back, a pair of base guides adapted to be adjusted longitudinally upon the back and to be secured thereto in a selected adjusted position, an intermediate base spanning the inner ends of the base-guides and being longitudinally adjustable therein, and bases longitudinally adjustably mounted within the base-guides outwardly of the intermediate base, and holding elements carried by the bases. 35 40 45

3. In a loose-leaf binder, a cover having a back, a pair of base-guides, an intermediate base telescoping the inner ends of the base-guides, outer bases telescoping the outer ends of the base-guides, holding elements carried by the bases, and means for attaching the base-guides to the back. 50

4. In a loose-leaf binder, a pair of base-guides, a base telescoping with the inner ends of the base-guides, outer bases telescoping with the outer ends of the base-guides, and holding elements carried by the bases. 55

In testimony whereof I affix my signature.

SIDNEY G. MEWBORN.
